UNITED STATES PATENT OFFICE

AAGE E. WINCKLER, OF MILWAUKEE, WISCONSIN

INTERNAL COMBUSTION ENGINE

Application filed June 24, 1929. Serial No. 373,160.

The invention relates to internal combustion engines.

In the operation of engines designed for aeronautic purposes, the amount of compression of the combustible mixture effected in the cylinders varies according to the density of the air which varies in different altitudes. This causes less compression and a corresponding reduction in power when the engine is operated in high altitudes. To compensate for this variation, it has heretofore been proposed to adjust the piston stroke in an engine of the single crank type, as set forth in Patent No. 1,174,459 dated March 16, 1917.

One object of the present invention is to provide an engine having a plurality of cranks with mechanism which is operable while the motor is running for varying the length of the effective stroke of the pistons, so that the necessary compression for efficient combustion and power can be maintained in air of different densities or in different altitudes.

Another object of the invention is to provide an engine having more than one crank with mechanism which comprises elements such, for example, as eccentrics on the crank-pins for varying the length of the piston-strokes in which the power stresses transmitted from the pistons to one crank, which tend to shift or rotate one element relatively to its crank-pin, will counteract or neutralize the stresses tending to shift the other element relatively to its crank-pin. By thus neutralizing these displacing forces resulting from the power stresses, the elements may be easily adjusted while the engine is in operation, because the stresses applied to one element are balanced by the stresses applied to the other element, so the elements will remain in equilibrium and be free to be shifted without resistance by the power stresses.

A further object of the invention is to provide efficient means for conjointly adjusting eccentrics on a plurality of cranks to vary the length of the piston strokes.

Other objects of the invention will appear from the detailed description.

The invention consists in the several novel features hereinafter set forth and more par-

ticularly defined by claims at the conclusion hereof.

In the drawings: Fig. 1 is a longitudinal section of an engine embodying the invention, the crank-shaft and mechanism rotating therewith being shown in elevation. Fig. 2 is a section on line 2—2 of Fig. 1. Fig. 3 is a section on line 3—3 of Fig. 1. Fig. 4 is a longitudinal section. Figs. 5 and 6 are diagrammatic views illustrating the relative position of the eccentric in different adjustments, to produce relatively long and short piston strokes. Fig. 7 is a section on line 7—7 of Fig. 4.

The invention is exemplified in an engine comprising a crank case 8; a circular series of cylinders 9 in a common plane; a circular series of cylinders 9^a in a common plane, disposed longitudinally of the series 9; a crank shaft 11 journalled in bearings 16 and 17 in the crank-case; a series of pistons 12 slidable in the cylinders 9; connecting rods 13 respectively pivoted to wrist-pins 14 in pistons 12 and connected to rings 15 around a crank pin 10; a series of pistons 12^a slidable in the cylinders 9^a respectively; connecting rods 13^a respectively, pivoted at their outer ends to wrist-pins 14^a in pistons 12^a, and at their inner ends to rings 15^a around a crank pin 10^a. Any suitable valve mechanism may be provided for the admission of combustible fluid to the cylinders and the exhaust of the products of combustion, as well understood in the art. The crank-pins 10 and 10^a are nearly diametrically opposite with respect to the axis of the crank-shaft 11, and are united to said shaft by crank members 11^c, 11^a, and are connected together by crank-member 11^e. An eccentric sleeve 18 is rotatably adjustable on the crank pin 10 and fits in rings 15. An eccentric sleeve 18^a is rotatably adjustable on the crank pin 10^a and fits in rings 15^a. By rotating the eccentric-sleeves 18, 18^a on their crank pins, the effective length of the cranks and the stroke of the pistons can be shortened or lengthened to vary the area of the compression space between the pistons and the cylinder heads, and the compression of the combustible mixture taken into the cylinders, if the air is of uniform density or to maintain

the compression uniform when the density of the air in which the engine is operating, varies.

Mechanism is provided simultaneously and 5 equidistantly to adjust the eccentric sleeves 18 and 18^a rotatively on the crank pins 10 and 10^a, and comprises a shaft 20 which is coaxial with and disposed in one end of the crank-shaft 11; a pinion 21, fixed to the inner 10 end of shaft 20; a gear-wheel 22 fixed to or integral with one end of the eccentric sleeve 18^a; a bevelled gear 23 rigid with the other end of eccentric 18^a; a bevelled pinion 24 meshing with gear 23; a shaft 25 which extends longitudinally through the crank-member 11^a and to which pinion 24 is fixed; a bevelled pinion 26 fixed to shaft 25; and a bevelled gear 27 fixed to or integral with one 15 end of eccentric 18 and meshing with pinion 26. This gearing constitutes a connection between the eccentric-sleeves, which moves bodily with the crank-shaft and which transmits rotative adjustment of one sleeve on its crank-pin in one direction to rotative adjustment of the sleeve in another crank in the opposite direction. A collar 28 is secured to one 20 end of shaft 25 to cooperate with gear 26 in holding the shaft against longitudinal movement in crank-member 11^a.

Shaft 20 is provided with double-screw threads 20^a of sharp pitch which engage corresponding internal threads in a sleeve 31 which fits and is slidable in one end of the 25 crank-shaft 11. The outer end of sleeve 31 is provided with radially projecting studs 32 which extend through, and are slidable in longitudinal slots 33 formed in said end of the crank-shaft. Sleeve 31 is rotatable with the crank-shaft and is slidable longitudinally 30 therein to rotate the screw-shaft 20 and pinion 21 for adjusting the eccentric sleeves 18, 18^a. The ends of studs 32 engage openings in a sleeve 34 which is slidably mounted on the crank-shaft, and a split collar 35 engages an 35 annular groove in said sleeve. One member of collar 35 is provided with a nut 36 which is engaged by a screw-shaft 37, which is journaled in a bracket 38 on the crank case, and has secured thereto a hand wheel 39. A collar 37', fixed to screw-shaft 37, with hand wheel 39, holds this screw-shaft against longitudinal movement in the bracket 38.

The outer end of screw-shaft 20 extends 40 through a cap 40 that fits on the end of crank-shaft 11 and is provided with a collar 41 which engages the outer face of the cap. The hub of pinion 21 abuts against crank-member 11^a, so that screw-shaft 20 is held against longitudinal movement but is free to be 45 rotated by the longitudinal shift of the sleeve-nut 31. By rotating screw 37 by means of wheel 39, the sleeve nut 31 is shifted longitudinally and the screw-shaft 20 is rotated to operate the eccentric adjusting mechanism.

To adjust the eccentrics 18, 18^a, hand-wheel

39 will be rotated. This wheel will rotate screw 37 which will shift nut 36 and collar 35 longitudinally, so that sleeve 34 and the screw sleeve 31 will be shifted to rotate shaft 20 by means of screw-thread 20^a. Shaft 20 will 70 rotate pinion 21 which meshes with gear 22 so that eccentric 18^a will be rotated around crank-pin 10^a to vary the strokes of pistons 12^a. Such rotation of eccentric 18^a will rotate gear 23 which will rotate pinion 24, shaft 25, 75 pinion 26, gear 27, and eccentric 18, so that the stroke of pistons 12 in cylinders 9 will be simultaneously and equidistantly adjusted with the eccentric 18 to correspondingly vary the length of the strokes of pistons 12 and 12^a. This adjustment may be effected while the motor is in operation.

The eccentrics 18 and 18^a are corelatively disposed on their crank-pins respectively so that the strokes of the pistons 12, 12^a will be 80 uniform. The gearing between the eccentrics is of such construction that when the eccentric 18 is rotated around crank-pin 10 in one direction, the eccentric 18^a will be rotated on crank pin 10^a equidistantly in the 85 relatively opposite direction. As a result, when wheel 39 is rotated, the eccentrics will be simultaneously and conjointly rotated in opposite directions through the gearing between the sleeves. The power stresses transmitted to the eccentrics and crank pins by the connecting rods and pistons, as indicated by the arrows in Figs. 5 and 6, will tend to displace or rotate the eccentrics in the same 90 relative direction around their respective crank pins. Since the gear connection permits rotation of the eccentrics only in relatively opposite directions, and the power stresses will tend to displace the eccentrics in the same relative direction around their 95 respective crank pins, the resultant displacing stresses on one eccentric will, through the interconnecting gearing, be opposed or counteracted by the displacing stresses applied to the other eccentric. For example, if the 100 engine is operated in the direction indicated by the arrows in Figs. 5 and 6, the power stresses will tend to rotate both eccentrics clockwise around their respective crank pins, but the gearing between the eccentrics will 105 permit only relatively opposite rotation thereof, and as a result, the power or displacing stresses applied to one eccentric will be opposed or counteracted and balanced by the stresses on the other eccentric. Therefore, the eccentrics and the interconnected 110 gearing, while moving bodily with the cranks and crank shaft, will be in equilibrium so that the power stresses will not resist the adjustment of the eccentrics to vary the piston 115 strokes. This eliminates resistance of the power stresses to the rotative adjustment of the eccentrics, and makes it possible to shift the adjustment by slight force, and there will be no tendency of the power stresses to 120

adjust the eccentric sleeves or cause unintentional variation of the piston stroke.

The invention exemplifies mechanism for varying the piston strokes in engines with a plurality of cranks which can be easily operated, in which there will be no tendency to displace the eccentric sleeves from the position in which they are adjusted; which can be readily operated while the engine is in operation, and in which the power stresses applied to the eccentrics which control the piston strokes are applied to oppose or neutralize each other to attain the advantages aforesaid.

While the invention has been described in connection with an engine with radial cylinders, it will be understood that it is applicable to other types.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In an internal combustion engine, the combination of a pair of engine cylinders, each having a piston mounted slidably therein, a crank-shaft provided with a pair of cranks, connecting rods extending between the cranks and the pistons, a pair of sleeve-like eccentrics mounted rotatably on the cranks and operative in response to rotation thereof relatively to the cranks, to vary the length of the piston strokes, and gearing on the crank-shaft forming a driving connection between the eccentrics and constraining the eccentrics when actuated to rotate in opposite directions so that the stresses applied to said one eccentric are transmitted so as to counterbalance the piston stresses applied to the other eccentric.

2. In an internal combustion engine, the combination of a pair of engine units arranged one in front of the other, each of said units comprising a plurality of radially extending cylinders with pistons mounted slidably therein, a crank-shaft for the engine provided with a pair of cranks, a set of connecting rods for one of the engine units extending between and connected operatively to one of the cranks and the pistons of said one unit, a set of connecting rods for the other unit extending between and connected operatively to the other crank and the pistons of said other unit, a pair of sleeve-like eccentrics mounted rotatably on the cranks and operative in response to rotation thereof relatively to the cranks, to vary the length of the piston strokes, and means on the crank-shaft forming a driving connection between the eccentrics and operatively to rotate one eccentric in a direction opposite from the other eccentric so that the stresses applied to

said one eccentric are transmitted so as to counterbalance the piston stresses applied to the other eccentric.

Signed at Chicago, Ill., this 20th day of June, 1929.
